DISPLAY DEVICE

Raffaele Floravanti, Milan, Italy, assignor, by
mesne assignments, to Biolite, Inc., New York,
N. Y., a corporation of New York

Application February 23, 1935, Serial No. 7,758
In Luxembourg August 20, 1934

5 Claims. (Cl. 40—130)

This invention relates to display devices and more specifically to illuminated signs.

In general, it is an object of the invention to provide a device of the character described, which will efficiently perform the purposes for which it is intended, which is simple and economical of construction, which can be expeditiously, conveniently and safely manipulated, and which can be readily manufactured and assembled.

Another object of the invention is to provide a transparent sign having moving liquid and gas elements therein; to provide such a sign wherein those gas elements all pass constantly toward the end of a closed tube; to provide such a sign which is illuminated and energized from the same source; and to provide such a sign having a plurality of similar units, all being in part above room temperature.

Another object is to provide a transparent sign having a lower passageway which does not tend to become clogged when a powdery solid is present, and in which the dye solution does not fade.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Fig. 1 is a front view in elevation and with a part broken away of a device embodying one form of the invention;

Fig. 2 is an end view in elevation and partly in section of the device shown in Fig. 1; and

Fig. 3 is an end view in elevation, partly in section and partly diagrammatic of a modification of the device shown in Fig. 2.

This invention contemplates a display device mounted preferably in a casing and having an exposed translucent part in which a liquid may be seen to bubble. Heat is supplied to give the energy required by the bubbling and light may be supplied to illuminate the liquid and the bubbles. The translucent part is in the form of an element such as a letter, a numeral, a sign, an emblem or a design or any combination thereof. The term "translucent" is intended to embrace the term "transparent".

The liquid occupies but part of the space within

the device, leaving a vapor chamber at either end thereof, and the pressure within the remainder of the space being at less than atmospheric at room temperature. A volatile liquid such as alcohol or ether is preferably employed and coloring matter may be added. Due to the special shape of the device, the liquid retains the color. In former devices the coloring material was quickly deposited on the heated walls, and the liquid faded to a colorless condition. The bubbling is attained by heating the lower end of the device whereby, as described below, a part of the liquid is gasified and passes through the remainder of the liquid to the top of the device when the normal room temperature causes the gas to condense and fall back as a liquid toward the bottom of the device.

The device may also contain a granular substance which will be agitated by the bubbling and which may cause the light to be reflected with a scintillating effect. This substance may be powdery in form, for example, crystals of magnesium carbonate. Certain substances of this type tend to clog narrow passages, particularly in the lower part of devices wherein they may tend to settle. The apparatus described below is designed to minimize or eliminate this difficulty.

In the form of the invention illustrated in Figs. 1 and 2, the device has a hollow element 10 which is, at least in part, translucent and which, in the type shown, is a letter of the alphabet. A vaporizing chamber 11 is provided which is at least in part below the hollow element.

A passageway 12 connects the lower part of element 10 with the vaporizing chamber 11 and has a portion comprising the lowest point in the device. Preferably when passageway 12 is at the lowest part of the device, element 10, which may be tubular or relatively tall compared to its breadth from front to back, has no portions from which liquid would fail to tend to drain into passageway 12.

As shown, the passageway 12 is bent downward, the two upward arms leading to element 10 and chamber 11, respectively, and its volume added to the volume of chamber 11, may be slightly less than the volume of element 10.

The volume of liquid when at operating temperature is about equal to almost the entire volume of the exposed part of element 10 plus that portion of passageway 12 which opens into element 10. As shown in Fig. 2, a pocket of vapor must remain in chamber 11 or the bubbling action will not begin.

Each display unit comprising the above-described parts, may be suitably mounted, as for example, by the casing 13. Clamps 14 which may be slideable along a portion of the casing may detachably hold some part of each bubbling device. Preferably the transparent element 10 extends out of the casing, the chamber 11 and passageway 12 being hidden within it. A source of illumination 15, not visible within the casing, supplies heat to the chamber 11 and, through some convenient opening, illumination for the element 10. Letters such as A, M or N may have a vaporizing chamber at the bottom of each leg.

The operation of the device is as follows:

15 The source of illumination 15 is lighted and communicates heat to the chamber 11, in which most of the liquid has settled. Some of the liquid is also held by the passageway 12. Since the latter is in a low part of the device, the granular or crystalline material will have settled and somewhat compacted there. As the liquid in chamber 11 becomes warmer it begins to vaporize and collect as a gas in the top of chamber 11. The pressure of this gas as it expands, forces all of 20 the liquid out of chamber 11 and through passageway 12 up into element 10. As the liquid passes through the mutual opening between chamber 11 and passageway 12, it is slantingly directed against the bottom of the passageway 12. 25 There is thus given a direct force which tends to sweep the granular material out of the passageway 12. When all the liquid has been forced out of chamber 11 and the arm of passageway 12 leading to chamber 11, the gas begins to bubble 30 past the lowest point of passageway 12 and up into chamber 10, where it becomes visible.

In certain devices where the tube 12 actually leads into and toward the bottom of chamber 11 which is beneath, the granular or powdery material collects on that bottom and chokes the entrance to the tube. The pressure in that case of the gas above tends to impact further the powdery material and is exerted downward while the powdery material must be lifted upward. The 45 present invention tends to overcome this packing tendency, rather than to aggravate it.

When the bubbles of gas reach the upper vapor space in element 10, they are relatively chilled and condense to return under gravity to passageway 12 and chamber 11, there to begin the cycle over again.

In Fig. 3 a modification is shown whereby heat is delivered to chamber 11 by a resistance wire independently of the source of illumination 15.

55 Since certain changes may be made in the above article and different embodiments of the invention could be made without departing from the scope thereof, it is intended that all matter contained in the above description or shown in the 60 accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a display device of the type described, a hollow translucent display element containing a liquid having an ornamental substance therein, an upwardly extending vaporizing chamber adjacent the lower portion of said element, a passageway between said chamber and the interior of said element, and means for establishing an oscillating liquid-vapor interface in said passageway, whereby deposits of said substance may be removed from said passageway and retained in said liquid. 5

2. In a display device of the type described, a hollow translucent display element containing a liquid having an ornamental substance therein, an upwardly extending vaporizing chamber adjacent the lower portion of said element, a passage between said chamber and the interior of said element, said passageway having a portion 20 thereof comprising the lowest point in said device, and means for establishing an oscillating liquid-vapor interface in said passageway, whereby deposits of said substance may be removed from said passageway and retained in said liquid. 25

3. In a display device of the type described, a hollow translucent display element containing a liquid having an ornamental substance therein, an upwardly extending vaporizing chamber adjacent the lower portion of said element, a passage between said chamber and the interior of said element, means for establishing a liquid column including all of said liquid, the lower end of said column being in said passageway, and means for reciprocating said column end in said passageway, whereby deposits of said substance are prevented from remaining in said passageway. 30 35

4. In a display device, a hollow translucent display element containing a liquid having an ornamental substance therein, an upwardly extending vaporizing chamber adjacent the lower portion of said element, a passageway between said chamber and the interior of said element, a heat source positioned adjacent said chamber, a liquid column supported in said element and having the lower end thereof in said passageway, said support comprising vapor pressure generated in said chamber, and means including variations in said vapor pressure for reciprocating the lower end of said column through said passageway, whereby deposits of said substance are prevented from remaining in said passageway. 45 50

5. In a bubbling display device, a hollow translucent display element, a liquid having an ornamental substance therein being contained in said element, an upper vapor chamber adjacent the top of said element, and a lower vapor chamber adjacent the bottom of said element, a passageway connecting said lower chamber with the interior of said element, said passageway comprising the lowest portion of said device, and means for maintaining said chambers at unequal temperature whereby said liquid reciprocates in the passageway and prevents substantial loss of said ornamental substance from said liquid. 55 60 65
